UNITED STATES PATENT OFFICE.

ABEL E. CHERNACK, OF NEW YORK, N. Y.

PHONOGRAPH-RECORD CABINET.

1,321,010.

Specification of Letters Patent.

Patented Nov. 4, 1919.

Application filed February 6, 1919. Serial No. 275,374.

To all whom it may concern:

Be it known that I, ABEL E. CHERNACK, a citizen of the United States, and residing in the city, county, and State of New York, 5 have invented a new and useful Improvement in Phonograph-Record Cabinets, of which the following is a specification.

My invention relates to phonograph record cabinets, and particularly to a shelf 10 arrangement which affords a graphic display of the records when the shelves are drawn out, and thus facilitates the identification and selection of the records contained within the cabinet.

15 In the accompanying drawings,

Figure 1 is a perspective of a cabinet in which my invention is embodied in one form;

20 Fig. 2 is a section on the line 2—2 of Fig. 1;

Fig. 3 is a section on the line 3—3 of Fig. 2;

Fig. 4 is a partial section on the line 4—4 of Fig. 2 drawn to a larger scale; and

25 Fig. 5 is a perspective of a group of record envelops for a single compartment.

Various types of record cabinets have heretofore been proposed in which an attempt has been made to facilitate the identification of the records carried by the shelves of the cabinet, but these have commonly necessitated an independent indexing system either associated with the shelves or arranged in some other part of the cabinet

30 by which the location of the records can be readily ascertained. Such systems have necessitated a numbering of the envelops and a cross-reference to this numbering in the index, and furthermore it has required

35 that the records be returned to precisely the same position in the cabinet after use in order to maintain the indexing system. In the usual home use of records it is a common occurrence to find the records carelessly re-

40 turned and the indexing systems disarranged so that they are practically of no use. By the present invention I have provided a cabinet in which the shelves are so arranged, and the record envelops are of such character

45 that when the shelves are pulled out they automatically display the envelops in such fashion as to form an index of the entire series of records in the unit, and the only essential to the maintenance of the index

50 display is the requirement that the record be returned to its proper envelop, and the

latter returned to the cabinet in juxtaposition to an envelop having its index tab staggered with relation to that of the envelop returned.

60

In the accompanying drawings I have shown the invention embodied in a cabinet unit, but it is to be understood that the same features may be applied to a cabinet of larger size, having several units, or a single 65 larger unit; or again the cabinet may be made up of several units of the type shown, after the fashion of a sectional bookcase, in which event the units would be provided with interfitting means to secure their 70 proper registry and interengagement. Again, the shelf scheme may be built into cabinets such as are now common on the market.

As here shown, the cabinet unit comprises 75 a closed rectangular casing 10, provided at its front side with doors 11 and 12, to expose the interior of the cabinet. The unit may have short supporting legs 13, if it is to rest upon a table, or the corner pieces may 80 be extended downward as indicated in dotted lines at 14, if it is to stand upon the floor. Where the unit is merely a section of a built-up cabinet, the corner pieces 13 may be offset as at 15 to interlock in recesses 16 85 in the top of the unit, or any other suitable interengaging elements may be substituted for this feature.

Within the cabinet I have arranged a series of shelves, six in number, each comprising opposite side members 17 united by a back piece 18, and by a series of record supporting elements here shown as wire rods 19. These rods are here shown to comprise for each shelf horizontal groups of 95 three, spaced apart vertically to form four compartments. The spacing between the groups is sufficient to accommodate three records in each compartment. The rod groups are arranged on an inclined plane 100 with relation to each other to correspond to the beveled front edge 20 of the side members 17 of the shelf. Secured to the back piece 18 of each shelf are blocks 21, the forward faces of which are stepped to correspond with the rod groups and serve to hold the record envelops 22 for each compartment in stepped relation to the envelops of adjacent compartments. A group of three envelops for a single compartment is illustrated 105 in Fig. 5, and, as there shown, each envelop is provided at its front edge with a cut-out 23 on

the upper margin to facilitate the removal of the record, and an index tab 24 on the lower margin on which the title of the record may be entered. The index tabs for the 5 three envelopes of the group are staggered with relation to each other so that when the envelopes are juxtaposed the several titles are nevertheless fully disclosed for all three envelopes. By reason of this arrangement 10 of the index tabs of the envelopes, and the stepped arrangement of the compartments of each shelf, the titles of all of the records on each shelf are clearly displayed; nor is it necessary for this display that the same 15 relative arrangement of the envelopes for each compartment be maintained so long as in each compartment there is a group of envelopes having their index tabs 24 staggered as shown.

20 In order that there may be the least possible waste space in the cabinet incident to this arrangement of the records, I provide a sliding engagement between the several shelves such that while in housed position 25 within the cabinet the several shelves form a vertically superposed pile, yet when drawn out they are halted in stepped relation to each other so as to form an inclined pile which presents the index tabs of the entire 30 series of shelves as an inclined chart in which all are simultaneously visible. To this end the several shelves are mounted upon each other within a sliding tongue and groove engagement 25, 26, clearly shown in 35 Fig. 4. The bottom shelf is provided with bearing rollers 27 which rest upon the cabinet and insure the free action of the shelf group. A stop 28 carried by the top of the unit engages a notch 29 in the top shelf and 40 halts it when it is drawn out a sufficient distance to display the index tabs of the envelopes carried thereby. Stop blocks 30 secured to the lower edge of the side member 17 of each shelf work in notches 31 in 45 the upper edges of the subjacent shelf, and the notches are of such length as to halt the shelves in the stepped position shown. The bottom shelf is provided at its front margins with a cross bar 32 cut out at 33 to afford a hand grip. A supplemental stop 34 50 may be secured to the bottom of the unit to engage the back piece 18 of the bottom shelf and coöperate with the stop 28 at the top of the unit in halting the several shelves in their 55 predetermined "out" position. It is thus obvious that while the advantages of a complete display of the index tabs for the entire series of records of units is attained, there is the least possible waste space in the 60 cabinet when the shelves are in housed position, and the unit may therefore be made more compact than would otherwise be the case.

65 While I have shown the shelf compartments formed by wire rods 19, it is to be

understood that any other means may be used to form the partitions between the compartments; but the rods are relatively light as compared to sheet metal and are more rigid than the latter, so that they 70 completely support the record not only at its front and back margins, but across its mid area and thus prevent any tendency of the records to become deformed. While I have shown the unit as made from wood, 75 with the exception of the wire rods 19, and the several metal attachments, it is to be understood that the entire cabinet, or any part, may be made of sheet metal where this is preferable. Of course the vertical spacing 80 of the rod groups of the several shelves may be varied to accommodate more than three records if this is preferred, but I have found that three is the most satisfactory number since otherwise the index tabs become too 85 small for ready legibility of their entries. The arrangement of the supporting rods of adjacent compartments on an incline with respect to each other is not essential, so long as some means be provided for stepping the 90 record groups of the several compartments with relation to each other, such as the stepped abutment blocks 21. There is, however, a point of best support for the record in a wire rod arrangement of this type, and 95 it is preferable to maintain the points of support uniform throughout for this reason.

It should be pointed out also that the shelf pile, when drawn out, stands at such inclination and is halted in such position 100 that the center of gravity of the pile lies to the rear of the front support of the cabinet. There is consequently no danger of overturning the cabinet even when the shelves are fully loaded. Where a phonograph is supported on the top of the cabinet this feature is not of great importance 105 since its weight is sufficient to prevent overturning.

Various modifications in the details of 110 construction and arrangement which do not depart from what I claim as my invention will readily occur to those skilled in the art, and the construction as shown in the drawings and above described is to be regarded 115 as merely illustrative of the invention.

I claim:

1. In a phonograph record cabinet, a series of sliding drawers normally vertically superposed within the cabinet, shelves subdividing each drawer into a series of superposed stepped compartments each accommodating a group of record carriers having transversely staggered index tabs, together with means to halt said drawers in stepped 120 relation when the series is drawn out to afford a complete display of the index tabs of all the record carriers in the cabinet in vertically stepped groups with the tabs of each group transversely staggered. 125

2. In a phonograph record cabinet, a series of sliding record supports subdividing the interior of the cabinet into a series of superposed compartments, each accommodating a group of record carriers with transversely staggered index tabs, means to halt said supports in vertically stepped relation when the series is drawn out to afford a complete display of the index tabs of the series of record carriers in vertically stepped groups with the tabs of each group arranged in transversely staggered relation.
3. In a phonograph record cabinet, a series of sliding record supports subdividing the interior of the cabinet into a series of superposed compartments, each accommodating a group of record carriers with transversely staggered index tabs, means to halt said supports in vertically stepped relation when the series is drawn out to afford a complete display of the index tabs of the series
- of record carriers in vertically stepped groups with the tabs of each group arranged in transversely staggered relation, said record carriers being independent of each other 25 and readily removable from the cabinet and being replaceable in any incomplete group lacking a carrier with index tab similarly placed, while maintaining the index display of the series complete irrespective of the 30 precise location of any record carrier in the cabinet.
4. In a phonograph record cabinet, a shelf having a series of wire rod groups forming record supports and abutment means at the 35 back of the shelf, stepped to insure the presentation of the record groups on the several rod groups in stepped relation at the front of the shelf.

In testimony whereof I have signed my 40 name to this specification.

ABEL E. CHERNACK.
